UNITED STATES PATENT OFFICE.

ROBERT F. LINDSAY, SR., OF GREENVILLE, SOUTH CAROLINA.

CAN BRACKET AND HANGER.

Application filed July 3, 1924. Serial No. 724,071.

To all whom it may concern:

Be it known that I, ROBERT F. LINDSAY, Sr., a citizen of the United States, residing at Greenville, in the county of Greenville 5 and State of South Carolina, have invented a new and useful Can Bracket and Hanger, of which the following is a specification.

This invention relates to a can bracket and hanger, especially adapted for use in connection with a device for agitating liquids by means of air while they are being frozen.

In manufacturing ice from raw water it is customary to agitate the water by means of air introduced through a perforated tube suspended in the central part of the can in order to remove impurities therefrom, and to prevent the same from being frozen into the ice as it is progressively formed from the walls of the can toward its center.

The object of the present invention is generally to improve the construction of the supporting bracket and the connection of the tube therewith, so that the bracket is always held in the proper position, and the tube has a floating support whereby it may automatically adjust itself to cans of different width, and to the space occupied by the core of unfrozen water therein. The invention also includes a bracket adapted to be easily attached to any of the different types of cans regardless of the distance of the lifting holes from the top of the rim, and it does not matter whether the cans have a plain rim with the lifting holes in the middle, or a can with ribs in the middle and the lifting holes at one side thereof. Another feature of the invention is an improved arrangement of the perforations in the tube, whereby its function is performed more uniformly and more efficiently.

The specific improvements by means of which the above and other desired results are obtained will be more fully explained in connection with the accompanying drawings which illustrate the invention in its preferred form.

In the drawings:

Figure 1 is a vertical longitudinal section 50 through an ice can, showing the invention in position.

Figure 2 is a vertical section taken at right angles to Figure 1.

Figure 3 is a horizontal section.

Figure 4 is a sectional view on an enlarged scale of the upper part of the can with the invention in position thereon.

Figure 5 is a detail view of the lower end of the tube.

Figure 6 is a detail view of the upper end of the tube, showing the air hose connection.

Figure 7 is a sectional view on an enlarged scale of a modified form of the invention.

Figure 8 is a detail view of the attaching yoke with a single prong dog.

Figure 9 is a plan view of the attaching bracket shown in Figure 7.

In the drawings there is shown an ice can 10, of conventional shape, disposed beneath a rectangular wooden frame 11, and containing a partially frozen block of ice 12, having an unfrozen core of water 13. An air lateral 14 is disposed along one side of the frame 11, which has a portion cut away, as shown at 15, to provide space for one or more depending valves 15^a, each provided with a nipple for attaching one end of an air hose 16. The other end of the hose is connected with a nozzle 17, having an angular tapered end adapted to seat within the upper end of the tube 18.

The tube 18 is provided with a substantially rectangular head 19 into which the upper end of the tube is expanded, and this head is adapted to fit and move freely within a channel shaped bar or support 20, which extends across the upper end of the can, as shown in Figures 2, 3 and 4. The bar 20 has an elongated opening 21 through which the tube is passed. The head 19 is of greater length and width than the opening 21. The bar 20 is formed at its ends into yokes 22 and 23 by which it is supported from the rim of the can. One of the yokes 22 is preferably formed with hook-shaped fingers 24 adapted to receive the rim of the can, while the other yoke 23 is provided with horizontal fingers 25 adapted to rest upon the rim at the opposite side of the can, thus allowing the hanger to be applied to cans varying considerably in width. A lug 26 is pivoted within each end of the channel bar 20, and is adapted to extend outwardly between the arms of the yoke into engagement with the adjacent lifting hole 27, usually formed at the upper end of the can midway between the edges thereof.

If the can is provided with a central rib and

the lifting hole is located at one side thereof, the lug 26 may be folded inwardly into the channel bar 20 where it is out of the way. Dogs 28 and 29 are pivoted within the channel bar 20 at opposite sides of its center and extend upwardly and outwardly above and beyond the rim of the can, one of the dogs being provided with a single prong 30, and the other dog being provided with two prongs, as shown at 31, which prongs are adapted to engage the inner faces of the wooden frame 11, so as to hold down the can and also prevent it from becoming laterally displaced. Each of the dogs 28 and 29 is extended upwardly and inwardly from its pivot to form a head or finger piece 32, by means of which it may be easily disengaged from the frame when the ice is to be harvested. The tube 18 is provided with a plurality of holes 33, equally spaced and arranged alternately on opposite sides of the tube, and progressively decreasing in diameter from the bottom to the top of the tube. In the modification shown in Figures 7 and 9, I have shown a channel bar 20^a, which differs from the channel bar 20 in that it extends only part way across the can and is supported entirely from the yoke 22 with hook-shaped fingers 24, the dog 29 with the double prongs 31 being used in connection therewith. A brace 34 secured to the under side of the channel bar 20^a engages the inner face of the can. The construction is in other respects similar to that shown in the other figures.

From the foregoing description, it will be seen that I have devised a can bracket and hanger which fits every type of can used for making artificial ice. In using it in connection with a can having plain sides with lifting holes in the center, the lugs 26 determine the position of the bracket centrally of the can, and owing to their pivotal connections they will fit into the lifting holes at different distances from the top of the rim. In the event that the can is ribbed in the center and the lifting hole at one side of the rib, the centering lug 50 is thrown back into the channel of the bar, and the arms of the yoke fit the sides of the rib to center the bracket. The dogs 28 and 29 automatically engage the inner faces of the wooden frame as soon as the bracket 55 is attached, and positively hold the can in position at the bottom of the brine, which, being denser than the fresh water in the can, has a tendency to buoy up the can. Another object of the holding down device is 60 that the can is held level, and the top of the block of ice is consequently made level and uniform, whereas in the absence of some means for positively holding the can, it is liable to tilt and to result in an uneven or 65 slanting top, making the block inconven-

ient to store, and making it impossible to cut it uniformly.

The channel shape of the bar 20 makes it strong and durable, and also forms a guideway for the head of the tube which 70 has a floating support. The elongated slot 21 permits a range of movement sufficient to allow the tube to adjust itself to cans of different width. It will also compensate for bent or distorted walls. Another ad- 75 vantage of this floating tube is that when the brine circulation is greater on one side of the can than on the other, so that transfer of heat is more rapid on one side, and the ice freezes faster on that side, the floating tube agitated by the discharge of air 80 automatically finds the center of the unfrozen zone, in other words, the unfrozen core, and when the two walls have frozen together and have met, the tube will be 85 at the meeting point. Thus, the block of ice when completed is clear throughout and has no core. In prior constructions where the tube is pivotally connected to the support it is confined in its swinging move- 90 ment to a single vertical plane. In the present invention the tube swings slightly out of a single plane, traversing a double elliptical area or describes in its motion the figure 8, which causes the tube to strike 95 different parts of the ice walls and prevents it from sticking and freezing in before the ice cake closes up. This result is due to the head 19 at the top of the tube in connection with the elongated slot 21 in 100 which the tube is caused to swing.

The bracket and hanger are very easily applied to the can, and just as easily removed. The shape of the yokes provides a wide bearing surface, and yet there is 105 plenty of room at the center of the can to remove the core and to refill without disturbing the hanger or tube. At harvest time, however, it is only necessary to press the heads 32 of the dogs down into the 110 channel to release them from the framework, so that the hanger or bracket is easily lifted out.

The size and arrangement of the holes 33 is also an important feature. These holes 115 are arranged at equal distances from each other, and alternately on opposite sides of the tube. Each hole is slightly less in diameter than the one below it. In practice, I have provided four holes, ranging in diameter from .04 inch down to .027 inch in 120 diameter, but, of course, the number and absolute sizes of the holes may be varied. By this arrangement, the air, which is under the least pressure, passes through the 125 greatest hole, and the distribution of the air is more uniform and results in a more efficient operation than is possible with tubes as heretofore constructed.

While the construction of the bracket and 130

hanger as herein described is to be preferred, it is, of course, apparent that various modifications may be made in the details thereof without departing from the salient features of the invention, which it is my purpose to cover in the appended claims.

What is claimed is:

1. An air agitating attachment for ice cans, comprising a tube and a support therefor, means for detachably securing said support to an ice can, and means for swingingly connecting the tube to the support and means for causing lateral swinging movement slightly out of a single vertical plane so that the tube traverses a double elliptical area which causes the tube to strike different parts of the ice walls, said connecting means also allowing the tube to rise automatically away from the support.
2. In an air agitating attachment for ice cans, the combination of a supporting bar having an opening, and a perforated tube with compressed air connections whereby air may be passed through the tube and perforations, said tube being suspended through said opening and small enough to be freely movable therein, a head on the tube located above the opening and resting on the upper surface of the bar adjacent the opening so as to positively limit the downward movement of the tube but permit the tube to swing freely to and fro and also to move upwardly independently of said bar.
3. In an air agitating attachment for ice cans, the combination of a supporting bar having an elongated opening, a perforated tube with compressed air connections whereby air may be passed through the tube and perforations, and means for suspending the tube through said opening, said means comprising a head in supporting relation to the upper end of the tube, said head being located above the bar and resting on the same adjacent the opening, said tube being small enough so that it may swing freely to and fro as well as rise vertically independently of said bar.
4. In an air agitating attachment for ice cans, the combination of a channel bar formed at one end with a yoke having arms and terminating in hook-shaped extremities adapted to fit over the rim of an ice can, said bar having an opening through the bottom of the channel, and a perforated tube whereby air may be passed through the tube and out through the perforations, said tube having a head fitting in the channel for suspending it through said opening, said head normally resting on the bottom of the channel and guided by the latter so as to permit the tube to swing to and fro and to rise with the head independently of the channel bar.
5. In an air agitating attachment for ice cans, the combination of a channel bar formed at one end with means adapted to fit over the rim of an ice can, said bar having an elongated opening through the bottom of the channel, a perforated tube with compressed air connections to the tube whereby air may be passed through the tube and out through the perforations, and means for suspending the tube through said opening, said means comprising a substantially rectangular head secured to the upper end of the tube and fitting within the channel and normally resting on the bottom of the channel so that the tube may swing to and fro and also rise in said opening independently of said channel bar.
6. A device for supporting agitator tubes for ice cans, having a channel bar with means at one end for engaging an ice can, and a pivoted lug carried by the bar and engageable with the lifting hole in said can, said lug being movable to lie within the channel when desired.
7. A device for supporting agitator tubes for ice cans, comprising a channel bar having means engageable with the rim of an ice can, a pivoted lug at one end of said bar engageable with the lifting hole in the can, said lug being swingable inwardly into the channel of said bar so as to be out of the way, an agitator tube, and means for suspending the tube from the channel bar.
8. A device for supporting agitator tubes for ice cans comprising a bracket, a hanger having means for detachably engaging the side of the can, an agitator tube supported by the bracket, means positively limiting the downward movement of the tube but permitting it to swing to and fro and to rise relatively to the bracket, and a dog pivoted to the bracket and having divergent prongs engageable with the frame surrounding the top of the can to hold down the can.
9. A device for supporting agitator tubes for ice cans, the cans having lifting holes therein, comprising a bracket provided with a means engageable with the side of the can, a pivoted lug engageable with the lifting hole in the can, an agitator tube supported by the bracket, means constituting a floating support for the tube to provide for the rise and fall of the tube as well as the swinging movement thereof, a frame outside the can, and means engageable with the frame surrounding the top of the can to hold down the can.
10. A device for supporting agitator tubes for ice cans, comprising a bracket and hanger provided with a means engageable with the side of the can, a pivoted lug engageable with the lifting hole of the can, an agitator tube having a head, a channel bar for receiving the head of the agitator tube and having an elongated slot in the bottom of the channel through which the

- 4
- the channel bar to limit the downward movement of the tube, but permitting it to swing to and fro and to rise relatively to the channel bar.
15. An agitator tube for ice cans, having a plurality of perforations equally spaced and arranged alternately on opposite sides of the tube, said perforations progressively increasing in diameter from the top to the bottom substantially proportionately to their distance from the tube of the surrounding water. 50
16. An agitator tube for ice cans provided at its upper end with an air hose connection, and having a substantially rectangular supporting head secured thereto beneath said connection, said tube being provided with a plurality of perforations equally spaced and arranged alternately on opposite sides thereof, said perforations progressively increasing in diameter from the top to the bottom of the tube substantially proportionately to their distance from the tube of the surrounding water. 55
17. A device for supporting agitator tubes for ice cans, provided with pivoted dogs having divergent prongs adapted to extend over the top of the can and engageable with a frame surrounding the same to hold down the can. 60
18. In a device for supporting agitating tubes for ice cans, the combination with a supporting bar having means for detachably engaging the ice can, an agitator tube, means for suspending the tube from substantially the center of the bar, dogs pivoted to the bar at opposite sides of its center and extending outwardly and upwardly above and beyond the rim of the can, said dogs each having operating finger pieces and also having a prong or prongs adapted to engage the inner face of a wooden frame which surrounds the ice can, whereby the latter is held down. 65
- In testimony, that I claim the foregoing as my own, I have hereto affixed my signature. 70
- ROBERT F. LINDSAY, Sr. 75
14. A device for supporting agitator tubes for ice cans having means at each end for engaging the sides of the can, an intermediate portion comprising a channel bar with an elongated slot in the bottom of the channel through which the tube may be suspended, one or more dogs pivoted to the channel bar and having divergent prongs adapted to extend over the top of the can and engageable with a frame surrounding the same, a tube, and means on the tube cooperating with 80
15. A device for supporting agitator tubes for ice cans, provided with ends detachably engageable over the sides of the can, a pivoted lug at each end engageable with a lifting hole in the can, an agitator tube, the intermediate portion of the device constituting a full floating support for the tube, and pivoted dogs carried by the supporting device and having prongs adapted to extend over the top of the can and engageable with a frame surrounding the same to hold down the can. 85
16. A device for supporting agitator tubes for ice cans, comprising means for detachably engaging the side of the can, and an agitator tube having a head, a channel bar for receiving the head of the agitator tube and having an elongated slot in the bottom of the channel through which the tube may be suspended with the head above the slot, and means connected with the said bar engageable with a frame surrounding the top 90
17. A device for supporting agitator tubes for ice cans, comprising means for detachably engaging the side of the can, means extending more than half way across the can and having an opening through which the tube may be suspended, and a dog pivoted to one of said means and having divergent prongs adapted to extend over the top of the can for engaging a frame surrounding the same to hold down the can. 95
